UNITED STATES PATENT OFFICE.

JOHN R. PEPIN, OF CHICAGO, ILLINOIS.

ELECTRIC-ARC LAMP.

SPECIFICATION forming part of Letters Patent No. 626,190, dated May 30, 1899.

Application filed October 28, 1898. Serial No. 694,810. (No model.)

To all whom it may concern:

Be it known that I, JOHN R. PEPIN, a citizen of the United States, residing in the city of Chicago, in the county of Cook and State 5 of Illinois, have invented certain new and useful improvements in Electric-Arc Lamps; and I do hereby declare that the following is a full, clear, and exact description of the invention, which will enable others skilled in the art to 10 it pertains to make and use the same, reference being had to the accompanying drawings, forming a part hereof, in which—

Figure 1 is a side elevation of my improved lamp, partly in section, through the axis of 15 the lamp, showing the electromagnet, the upper-carbon holder, piston, and dash-pot. Fig. 2 is a similar view of the lamp with part of the upper-carbon tube broken away and a flanged disk drawn in section to show the 20 clutching and suspension devices in position when the lamp is in action.

The object of the invention is to construct an electric-arc lamp in which the operative mechanism is reduced to a few parts of simple and cheap construction and to obtain positive regulation of movements in direct line 25 by the electric current and gravitation, to reduce the size and cost of electric-arc lamps, and to improve generally the construction and 30 operation of the electric-arc lamp; and its nature consists in the several parts and combinations of parts hereinafter described, and pointed out in the claims as new.

In the drawings, A is a bobbin, with flanges 35 C C.

S is the solenoid wound on the bobbin A.

B in Fig. 1 is a tube extending through the bobbin A, the top of the tube being closed.

E E is a bridge supporting the bobbin A 40 and solenoid S.

F is a flanged disk to which the bridge E E is attached.

Y Y are rods fastened to a ring attached by screws to the inner side of the flanged disk F.

45 These rods support the lower-carbon holder and the globe-holder.

G is the upper-carbon-holding tube, inclosed at the top. From the top of this tube a piston-rod and piston extend into the dash-pot

50 formed by the closed top of the tube B, as shown at D and θ. The bottom of the tube

G is slotted, as shown at W and W', and has an extension lug and pivot, as shown at L.

H is a plunger or soft-iron core affixed to the upper-carbon-holding tube G and is movable 55 up or down in the tube B.

I is a collar fastened by a set-screw to the tube G to limit its downward movement.

O is a bracket attached to the under side of the flanged disk F.

K is a clutch pivoted on the lug L at the bottom of the carbon-holding tube G.

M is a rod pivoted to the clutch K and extending through a hole in the bracket O, the rod being threaded at the upper end and provided with the nuts R R'. 65

T is a pendulum-rod hung to an eye attached to the under side of the flanged disk F.

V is a shoe attached to the lower end of the pendulum-rod T.

Z is the lower globe and carbon holder, resting on the brace-plate which secures the rods Y Y and is pivoted on the rod Y, on which it swings, and is adjusted either in or out of position by the thumb-nut α.

70 β is a hook to hold the globe while the lamp is being trimmed.

In use the operation of the lamp is as follows: The thumb-nut α is released and the globe and carbon holder Z is turned at right angles to the brace-plate which holds the rods Y Y. The upper carbon is then inserted 80

into the tube G and the lower carbon into the lower-carbon holder Z and the globe placed over the same and swung, with the lower carbon, into position and locked with the thumb-nut α.

Before the electric current is turned on the operative mechanism is in position as shown in Fig. 1. The collar I rests on the flanged disk F, supporting the tube G, with 85

its plunger H and piston θ. The rod M is suspended by the nuts R R', which rest on the bracket O. The upper carbon rests on the lower carbon and is perfectly free in the tube G. The clutch K is held by the rod M from 90

contact with the upper carbon, as shown at the slot W'. The shoe V on the pendulum-rod T rests against the tube G, above the slot W. The solenoid S and the arc X are 95

in series. When the circuit is closed, the core or plunger H is drawn upward into the tube B, as shown in Fig. 2, and the piston θ

is pushed into the upper part of the tube or dash-pot, retarding the movement of the core or plunger H, both up and down. In the upward movement the weight of the rod M and clutch K causes the clutch K to fall against and clutch the carbon X, as shown in Fig. 2, and lifting it with the tube G the arc $\mathcal{E}$ is struck. Thus H, G, θ , I, K, M, and X form a system. As the carbons burn away the resistance of the arc increases, and in obedience to gravitation the system H, G, θ , I, K, M, and X gradually falls till the nut on the rod M rests on the bracket, as shown at P in Fig. 1. The nut R comes in contact with the bracket O before the collar I reaches the flanged disk F, and as the tube G continues to descend after the nut on the rod M rests on the bracket O the free end of the clutch K is lifted by the rod M, freeing the carbon X. The lamp feeds and the plunger, together with the tube G and rod M, rises and causes the clutch K to again engage and clutch the carbon X. This movement is repeated till the upper carbon burns away, so that its top passes below the slot W, Fig. 2, and allows the shoe V to fall into the slot catching the tube G, and thereby suspends the whole system. As the carbon burns away the resistance of the arc increases until $R > \frac{E}{C}$, when the circuit breaks and the lamp is dead.

What I claim as new, and desire to secure by Letters Patent, is—

1. The combination in an electric-arc lamp

of an electromagnet, a central tube, a soft-iron core, a tube within said core, a rod and piston, a clutch pivoted to a lug on said tube, a rod pivoted on said clutch, a bracket, a flange or base supporting a magnet, a carbon held in the carbon-holding tube, and a collar adjusted by a set-screw to a carbon-holding tube adapted to hold the tube and the carbon when the lamp is dead, substantially as described and for the purposes specified.

2. The combination, in an electric-arc lamp, of an electromagnet, a central tube with closed top, a soft-iron core or plunger, a tube through the center of said core and affixed thereto, said tube having a closed top, a piston-rod and piston extending from and affixed to the top of said tube, a clutch pivoted to the lower end of said tube, a rod pivoted to the free end of said clutch, a bracket to guide said rod, and to support the nuts thereon and operate the clutch, a flanged disk or base supporting the magnet, a bracket and eye on its under side, a carbon held within a carbon-holding tube, clutched by a clutch pivoted at its lower end, with a pendulum-rod hung on an eye attached to the under side of the flanged disk or base, said pendulum-rod having a shoe affixed thereto, substantially as described and for the purposes specified.

JOHN R. PEPIN.
